United States Patent Office

Des. 221,984

Patented Sept. 21, 1971

221,984

TABLE LAMP

Donald R. Kracke, 5620 Whitecliff Ave.,
Palos Verdes Peninsula, Calif. 90274

Filed July 27, 1970, Ser. No. 24,145

Term of patent 14 years

Int. Cl. D26—05

U.S. Cl. D48—20

Fig. 1

Fig. 2

Fig. 3

Fig. 4

FIG. 1 is a front perspective view of a table lamp, showing my new design;

FIG. 2 is a rear elevational view thereof;

FIG. 3 is an elevational view of the side not shown in FIG. 1;

FIG. 4 is a bottom plan view thereof.

I claim:

The ornamental design for a table lamp, substantially as shown.
